Patented Jan. 8, 1918.

FIG. 3.

By

A. McWilson
Attorney

UNITED STATES PATENT OFFICE.

WILLIAM KOSTIW, OF BUFFALO, NEW YORK.

SHIP-PROTECTOR.

1,252,814.

Specification of Letters Patent.

Patented Jan. 8, 1918.

Application filed October 8, 1917. Serial No. 195,359.

To all whom it may concern:

Be it known that I, WILLIAM KOSTIW, a subject of the Emperor of Austria, residing at Buffalo, in the county of Erie and State 5 of New York, have invented certain new and useful Improvements in Ship-Protectors, of which the following is a specification.

This invention relates to certain new and 10 useful improvements in ship protectors.

The primary object of the invention is the provision of a device adapted for arrangement upon the hull of a ship for stopping torpedoes before striking the hull and for 15 holding the torpedoes positioned without contacting the exploding device at the forward pointed end thereof.

A further object of the device is to provide the hull of a ship with means arranged 20 adjacent the water line thereof adapted for catching and holding on-coming torpedoes in spaced relations from the hull, the arrangement being such as not to impede the travel of the boat through the water.

25 A still further object of the invention is to provide a means for catching torpedoes and not permitting the torpedoes to explode, such device being easy and inexpensive to manufacture as well as to install wherever 30 desirable such as upon the hull of a ship.

In the drawing forming a part of this application and in which like designating characters refer to corresponding parts throughout the several views,

35 Figure 1 is a side elevation of a ship provided with the present device.

Fig. 2 is a top plan view thereof with a torpedo illustrated by dotted lines as being held by the device, and

40 Fig. 3 is an enlarged vertical section through a side portion of the ship with a torpedo illustrated by dotted lines.

My device may be arranged in connection with any object which it is desired to 45

protect from oncoming missiles and is herein illustrated as positioned adjacent the water line of the hull 10 of a ship 11 having a cabin 12, funnels 13, pilot house 14, wireless outfit 15, propellers 16 and rudders 17.

50 A plurality of strips 18, here illustrated as three in number, are arranged in parallelism at opposite sides of the hull 10 being secured thereto by suitable hold-fast devices

19. Each of the strips 18 is provided with a multiplicity of equally spaced spurs 20 of 55 metal or other material of the requisite pressure or force resisting character for the intended purpose, V-shaped in form, and positioned in staggered relations upon the separate strips.

60 A torpedo such as 21 moving toward the hull 10 will force its pointed forward end 22 between different ones of said spurs 20 and by reason of the inclined sides 23 and sharp outward edges 24 of the spurs, it will 65 be impossible for the point of the torpedo to strike any object so as to contact the point with sufficient force to explode the torpedo. Also, the spurs 20 will receive the torpedo 21 wedged therebetween and the torpedo will 70 be prevented from striking the hull 10 and will be held in a harmless position.

75 T-shaped guards 25 may be carried by the bow 26 of the hull 10 serving as a sweep for floating mines. It will be understood that if the torpedo strikes the forward cutting edge 24 or one of the inclined sides 23 of one of the spurs 20, only a glancing blow will result and the torpedo will fail to explode. A safety device is arranged by 80 means of which a boat may travel near submarines without being endangered by torpedoes which are fired therefrom.

What I claim as new is:—

1. A ship protector comprising a plurality 85 of strips adapted for attachment to the exterior of a hull, and V-shaped spurs arranged equally spaced apart upon the said strips and alternately positioned upon adjacent strips.

90 2. A ship protector comprising elongated mounting means arranged in parallelism adjacent the water line of the hull and outwardly projecting V-shaped spurs equally spaced apart and alternately positioned upon the said mounting means and having sharpened free ends.

100 3. A ship protector comprising elongated mounting means arranged in parallelism adjacent the water line of the hull, outwardly projecting V-shaped spurs equally spaced apart and alternately positioned upon the said mounting means and having sharpened free ends, hold-fast devices for the said mounting means, the spurs being adapted 105 for the holding reception of a missile there-

between with the point thereof spaced from the hull upon which the device is arranged.

4. A device of the type described including a strip adapted to be applied to the hull of a vessel adjacent the water-line, said strip being equipped with V-shaped spurs, with their bases or flared portions positioned ad-

jacent to each other, their pointed ends diverging from each other to provide for receiving for a limited extent therebetween an 10 end-pointed or tapered missile or projectile.

In testimony whereof I affix my signature.

WILLIAM KOSTIW.
